United States Patent

Des. 238,332

Patented Jan. 6, 1976

238,332

BOTTLE

Robert Blosser, Sausalito, Calif., assignor to Grocery Store Products Company, Oakland, Calif.

Filed Sept. 24, 1973, Ser. No. 399,935

Term of patent 14 years

Int. Cl. D9—01

U.S. Cl. D9—127

FIG. 1.

FIG. 1 is an elevational view of a bottle embodying my new design;

FIG. 2 is a top plan view; and

FIG. 3 is a bottom plan view thereof.

The sides opposite those seen in FIG. 1 are the same in appearance as the sides shown.

I claim:

The ornamental design for a bottle, as shown and described.
